UNITED STATES PATENT OFFICE.

BERNARD F. KOCH, OF CHICAGO, ILLINOIS, ASSIGNOR TO ANGSTEN-KOCH COMPANY, OF CHICAGO, ILLINOIS, A CORPORATION OF ILLINOIS.

CYCLE-LOCK.

1,194,034.

Specification of Letters Patent.

Patented Aug. 8, 1916.

Application filed October 23, 1912. Serial No. 727,389.

To all whom it may concern:

Be it known that I, BERNARD F. KOCH, a citizen of the United States, residing at Chicago, in the county of Cook and State of Illinois, have invented certain new and useful Improvements in Cycle-Locks, of which the following is a description.

My invention belongs to that general class of devices known as locks, and relates particularly to a device for locking motorcycles, bicycles and the like, to prevent the same from being stolen or used without authority.

While the lock is particularly designed for use on motorcycles and the like, it may, however, be used wherever found applicable.

The invention has among its objects the production of a device of the kind described that is simple, efficient, compact, and satisfactory, and that cannot be easily tampered with or unlocked without the proper key.

To this end my invention consists in the novel construction, arrangement and combination of parts herein shown and described, and particularly pointed out in the claims.

In the drawings, wherein like reference characters indicate like or corresponding parts, Figure 1 is a front elevation of the device, and a portion of the two front forks of a motorcycle. Fig. 2 is a sectional view taken substantially on line 2, 2 of Fig. 1. Fig. 3 is a side elevation of one of the brackets and lock. Fig. 4 is a sectional view taken substantially on line 4, 4 of Figs. 3 and 5. Fig. 5 is a sectional view taken substantially on line 5, 5 of Fig. 4. Fig. 6 is a view in elevation of the locking bolt removed from the brackets, and Fig. 7 is a perspective view of the cam member 21.

Referring to the drawings, 1 and 2 represent one of the forks of the motorcycle, preferably the front fork, which is carried by the wheel (not shown) in the usual manner. The lock consists of a suitable bar adapted to pass between the spokes on the inner side of the rim, and suitable brackets for securing and locking the bar to the forks. The bar 3 is preferably formed of very hard material, for example case hardened steel, and pivoted at one end 4, and with a notch 5 proximate the opposite end. This last mentioned end is also preferably rounded, or similarly formed, as shown in

the drawings. The bar is secured to one fork, as shown to the fork part 2, by a bracket consisting of the parts 6 and 7, which are secured together by screws or bolts 8, clamping the bracket parts together and to the fork. The bar is adjustably and pivotally secured to the bracket part 6 through a member 9. The member 9 is pivotally secured to the bracket, the same being provided with a flange 10, between which and the flange 12 on the bracket part is arranged a spring 11. The bar is slidable in the member 9, so that it may be withdrawn from the opposite bracket, as hereafter described, and turned down substantially as indicated by the dotted lines in Fig. 1, when not in operation. The spring maintains the bar firmly in position and prevents rattling when the same is in inoperative position, and the vehicle on the road. It will be noted by referring to Figs. 1 and 2, that the bracket part 6 is slightly grooved at 34, so that when the bar is turned to inoperative position, it is held in the groove by the spring. Secured to the other fork part, as shown to the part 1, is a bracket consisting of the parts 14 and 15, which are secured together by bolts or screws 16. The bracket part 14 is extended as at 17 to form a chamber for a spring or locking member 19, having extended ends or arms 20, and is extended at one side at 18 to form a chamber for the insertion of the lock casing 23.

The lock shown is substantially similar to the well known cylinder lock, or the like, of which practically no two locks may be operated by the same key. In the lock shown, there is provided a rotatable lock cylinder 22, in which the key 24 may be inserted. When the key is turned the lock cylinder 22 turns with it. On the end of the lock cylinder 22 is arranged a cam member 21, which is positioned between the ends 20 of the spring, so that the same may be spread or separated when desired. The cam member is provided with a flange 27, and is secured to the cylinder by screws or bolts 26, or their equivalents, one part being preferably recessed, as shown the cylinder 22, to receive a bead 25 on the opposite part, so as to give a more rigid construction. The flange 27 securely locks or prevents the withdrawal of the cylinder 22, when the device is locked up, since it engages with the spring ends 20. As most clearly shown in Fig. 5,

when the cam member 21 and cylinder 22 are rotated, the ends 20 are spread apart, moving the same out of the notch 5 in the bar 3, so that the bolt 3 may be withdrawn and turned down, as indicated in Fig. 1, unlocking the cycle. When the lock is constructed as shown the bar 3 may be inserted in the opening through the bracket part 17 without unlocking the same, as the end of the lock 10 bar spreads the ends 20. As the bolt is pushed through, the ends 20 engage in the notch 5 as soon as the bar is pushed in sufficiently. It will be noted that the same cannot be unlocked by pushing the bolt through, 15 since the corners of the notch 5 are square, and the bar can only be released by spreading the ends 20.

It will be particularly noted by referring to Figs. 1, 2 and 3, that when the lock bar 3 is in locking position, the same substantially covers the heads of the screws 8 and 16, preventing the removal of the brackets from the fork. It will also be noted that since the 20 part of the lock bar is of some length, the bar cannot be struck down enough, or bent 25 so as to expose the screws holding the bracket bars together. While I have particularly described and shown a key lock, I do not wish to be understood as limiting myself to that, 30 as it is obvious that any other locking mechanism may be employed for controlling and operating the cam member 21, the type of lock shown, however being particularly desirable because of its simplicity, and well-known security.

Having thus described my invention, it is obvious that various immaterial modifications may be made in the same without departing from the spirit of my invention, 40 hence I do not wish to be understood as limiting myself to the exact form, construction, arrangement and combination of parts herein shown and described, or uses mentioned.

What I claim as new and desire to secure 45 by Letters Patent is:—

1. In a cycle lock of the kind described and in combination, a pair of brackets, means for securing said brackets to one of the forks of the cycle, one on each side of the wheel, a 50 locking bar, means carried by one bracket for slidably and pivotally securing the bar thereto, comprising a member pivotally secured to the bracket and arranged to slidably carry said bar, said bracket provided with a 55 groove across the face of the same, and resilient means arranged between the bracket and said member for maintaining said bar in said groove when the bar is out of operative position, and key-controlled means carried by the other bracket for locking said bar in operative position, as desired.

2. A cycle lock of the kind described and in combination, comprising a locking bar, a pair of supporting brackets therefor, comprising two parts, means arranged at points between the bracket parts and locking bar for securing the bracket parts together, one bracket provided with a bar carrying member pivotally and resiliently secured in operative position on the bracket, said bar being slidably carried by said member, the other bracket provided with a chambered extension and locking member arranged in said chamber, and provided with parts extending 70 to each side of said bar and arranged to engage the same when in operative position, a rotatable cam member arranged between said parts, and a key-controlled cylinder extending 75 into said chambered extension and secured to said cam member.

In testimony whereof, I have hereunto signed my name in the presence of two subscribing witnesses.

BERNARD F. KOCH.
